APPARATUS FOR THE PRODUCTION OF
DOT-COMPOSED NEGATIVESLudwig Mies van der Rohe and Walter Peterhans,
Chicago, Ill.

Application June 26, 1946, Serial No. 679,308

4 Claims. (Cl. 88—24)

1

This is a continuation-in-part of patent application Ser. #430,974, filed February 14, 1942, now abandoned, the latter being a continuation-in-part of patent application Ser. #252,654, filed January 24, 1939, which has matured into Patent #2,282,337 on May 12, 1942.

Our invention relates to photography, and more particularly to an apparatus for the production of dot-composed or screened negatives.

The conventional apparatus for the production of dot-composed negatives require the use of a half-tone screen of substantially the same size as the negative. Half-tone screens are comparatively expensive, and, if a half-tone screen exceeds a certain size, the costs of manufacture of such large half-tone screens becomes so high, that they are burdensome for the trade. Therefore, hitherto placards or other large sheets bearing reproductions of images have been usually manufactured in such a manner, that a plurality of small dot-composed negatives are produced by the use of small half-tone screens and an equal number of electrotypes are prepared from said negatives. Each of said electrotypes is used for the reproduction of images forming a portion of the entire image on small sheets, and several individual small sheets are then pasted on a board to form in combination a placard showing the entire image.

An object of our invention is to provide an apparatus, by means of which a small half-tone screen may be used for the production of a continuously coherent dot-composed reproduction of a positive on a negative of any larger size than that of the half-tone screen, so that the available half-tone screens of small size only may be used for the production of large sheets bearing reproductions, such as placards, wallpaper, etc.

With the above and other objects of the invention in view, the invention consists in the novel construction, arrangement and combination of various devices, elements and parts, as set forth in the claims hereof, certain embodiments of the same being described in the specification and being illustrated in the accompanying drawings forming part of this specification, wherein:

Fig. 1 is a diagrammatic top plan view, partly in section, of an apparatus according to the invention.

Fig. 2 is a view of a portion of a half-tone screen and a mask in an enlarged scale,

Fig. 3 is a diagrammatic view of a negative and a half-tone screen, the latter being shown in its starting position and in its end position,

2

Fig. 4 is a diagrammatic top plan view, partly in section, of another embodiment of an apparatus according to the invention, wherein the half-tone screen is moved step by step,

5 Fig. 5 is an elevational view of the half-tone screen and the mask of the apparatus shown in Fig. 4, in an enlarged scale,

Fig. 6 is a sectional view taken on line 6—6 of Fig. 5,

10 Fig. 7 is a fragmentary elevational view of a half-tone screen and a mask equipped with automatic means for causing a predetermined step-by-step movement of the half-tone screen,

Fig. 8 is an elevational view, partly in section, 15 of a latch mechanism shown in Fig. 7, and

Fig. 9 is a diagrammatic perspective view of the shutter, the objective, the half-tone screen, the mask, and driving means of another embodiment of an apparatus according to the invention, 20 wherein the half-tone screen is continuously moved.

Referring now to Fig. 1, 10 generally indicates a camera, which is mounted on a base 12 in any suitable manner. A mounting 14 rigidly secured 25 to the base 12 by suitable means is arranged opposite the objective 23 of the camera 10 having a lens 25. A positive 18 may be attached to said mounting 14 in any suitable manner. A negative 28 in the shape of a film or a plate may be attached to a stationary holder 32 arranged inside the camera 10. Thus, the positive 18 and the negative 28 are held in a fixed position with respect to each other and to the optical axis of the objective 23. An opaque endless belt or mask 30 surrounding the negative 28 is guided by rollers 42 rotatably mounted in a frame 44. Said mask 30 is provided with a window 54 receiving a half-tone screen 38 of a size smaller than the size of the negative 28. The half-tone screen 38 has a plurality of opaque dots 58 and transparent dots 59 as best shown in Fig. 2 in an exaggerated scale. According to Fig. 1, one of the rollers 42 is provided with a handle 56, so that the mask 30 and the half-tone screen 38 may be moved in close proximity to the negative 28 so as to place consecutive portions of the negative behind the half-tone screen. The portions of the negative not placed behind the half-tone screen are shielded by the mask 30. A shutter generally indicated 50 by 60, which may be actuated by a suitable wire release or trigger (not shown), may be used for exposing such consecutive portions of the negative 28 to corresponding consecutive portions of the positive 18. According to Fig. 2, the trailing edge 61 and the leading edge 62 of the window

54 of the mask 40 are parallel to each other. The distance d between said edges 61 and 62 is in such a predetermined relationship to the pattern of dots 58, 59 of the half-tone screen 30 arranged in the window 54, that the pattern of dots of the half-tone screen appearing in the window adjacent the trailing edge 61 represents a continuation of the pattern of dots of the half-tone screen appearing in the window adjacent the leading edge 62.

When the apparatus shown in Fig. 1 is used for the production of dot composed negatives by step-by-step movements of the half-tone screen 30 and the mask 40, at first the handle 56 is rotated so as to bring the half-tone screen 30 into a position in front of the portion a of the negative 28. When the half-tone screen 30 is at a standstill in said position in front of the portion a of the negative, a first exposure is made by an actuation of the shutter 60, so that the portion a' of the positive 18 is reproduced through the half-tone screen on said portion a of the negative 28. After said first exposure has been made, the handle 56 is turned so as to displace the half-tone screen 30 in the direction A through a distance equal to its width d appearing in the window 54 of the mask 40, whereby the half-tone screen is brought into a position in front of the consecutive portion b of the negative 28. Now, when the half-tone screen 30 is at a standstill in said position in front of the portion b of the negative, a second exposure is made by means of the shutter 60, so that the consecutive portion b' of the positive 18 is reproduced through the half-tone screen on said portion b of the negative. As will be readily understood from Fig. 2, said displacement of the half-tone screen 30 in the direction A through a distance equal to its width d brings the trailing edge 61 into a position previously occupied by the leading edge 62. Therefore, the pattern of dots produced during said second exposure by means of the half-tone screen 30 on the portion b of the negative 28 is in continuity with the pattern of dots produced during the first exposure by means of the half-tone screen on the portion a of the negative. After said second exposure, the half-tone screen 30 is again displaced in the direction A through a distance equal to its width d , until it reaches a position in front of the consecutive portion c of the negative 28. Thereupon, when the half-tone screen is at a standstill, a third exposure is made for reproducing the consecutive portion c' of the positive 18 through the half-tone screen on the portion c of the negative. Thus, a continuously coherent dot-composed reproduction of the positive composed of a plurality of separate reproductions of consecutive portions a' , b' , c' of the positive 18 is prepared. The dot composed negative thus obtained may be removed from the camera and may be used for the production of an electrotype according to any conventional process. Fig. 1 illustrates the three steps a , b and c for the production of a dot composed negative; it is understood, however, that a larger number of steps is used, when the width of the half-tone screen is smaller in proportion to the length of the negative.

According to the embodiment of an apparatus shown in Figs. 4-6, again the camera 110 is mounted on a base 112, and the positive 118 attached to the stationary mounting 114 and the negative 128 carried by the holder 122 are held in a fixed position relative to each other and to the optical axis of the objective 123. The half-

tone screen 130 is mounted in a carriage 163 having rollers 164 for engagement with stationary tracks 165, 166 arranged in the camera 110. The ends of a flexible opaque mask 140 laid around rollers 142 journaled in stationary parts of the camera 110 are secured to the carriage 163 by screws 167 in such a manner, that the trailing edge 161 and the leading edge 162 are in the same relationship to the pattern of dots of the half-tone screen 130 as described above in connection with the trailing edge 61 and leading edge 62 of the window 54 of the mask 40 shown in Fig. 2. The half-tone screen 130 arranged in the carriage 163 connected with the mask 140 may be moved along the tracks 165, 166 by rotating a handle 156 arranged on one of the rollers 142. A series of equally spaced indicating marks M_1 , M_2 , M_3 are arranged on the track 165. Said indicating marks M_1 , M_2 , M_3 are at a distance e from each other equal to the width d of the half-tone screen 130 appearing in the window 54 of the mask 140. Furthermore an indicating arrow or indicating means M is arranged on the carriage 163 for cooperation with said indicating marks M_1 , M_2 , M_3 . The indicating arrow M and the indicating marks M_1 , M_2 , M_3 are visible through a window (not shown) of the camera.

When the apparatus shown in Figs. 4-6 is used, at first the half-tone screen 130 is displaced along the tracks 165, 166, until the indicating arrow M is in register with the first indicating mark M_1 of the series of indicating marks M_1 , M_2 , M_3 , so that the half-tone screen 130 is in front of the portion a of the negative 128 as shown in Figs. 4 and 5. Now, when the half-tone screen 130 is at a standstill, a first exposure is made by an actuation of the shutter 160 for the reproduction of a portion of the positive on said portion a of the negative 128. After said first exposure, the half-tone screen 130 is moved by a rotation of the handle 156, until the indicating arrow M is in register with the second indicating mark M_2 , so that the half-tone screen is displaced one step through a distance equal to its width d into a new position in front of the consecutive portion b of the negative. When the half-tone screen is at a standstill in said new position, a second exposure is made. Thereafter, the half-tone screen is moved another step, until the indicating arrow M appears opposite the third indicating mark M_3 , so that the half-tone screen is in front of the consecutive portion c of the negative. Now, the half-tone screen being at a standstill, a third exposure may be made. Thus, the indicating marks M_1 , M_2 , M_3 in cooperation with the indicating arrow M represent spacing means serving as controlling means for the determination of the proper step-by-step movement of the half-tone screen, so that the exposures may be carried out at the proper moments when the half-tone screen is moved into a position wherein an exposure produces a pattern of dots on the negative in continuity with the pattern of dots produced by a preceding exposure.

Fig. 7 illustrates a mask and half-tone screen arrangement with mechanical controlling means for the step-by-step movement of the half-tone screen, which may be substituted for the mask and half-tone screen arrangement of the apparatus shown in Figs. 4-6. According to Fig. 7, the carriage 163 holding the half-tone screen 130 is slidably engaged with the stationary tracks 165, 166 arranged in the camera 110. The ends of the flexible mask 140 are secured to the carriage 163

in the same manner as described above in connection with Fig. 5, so that the edges 161 and 162 are in the proper relationship to the pattern of dots of the half-tone screen 130. A series of latch-mechanisms generally indicated by L₁, L₂ to be described hereinafter is attached to the track 165. The various latch-mechanisms are spaced from each other at equal distances, so that the distance *f* between the effective edge of the stopping means 168 of adjacent latch-mechanisms equals the width *d* of the half-tone screen 130 appearing in the window 154 of the mask 140. An abutting member 184 is attached to the carriage 163 for cooperation with the effective edge of the various stopping means 168. As best shown in Fig. 8, each stopping means 168 comprises a member 169 swingably mounted on a pin 170 arranged on the stationary track 165. An adjusting screw 171 having the effective edge 172 for cooperation with the abutting member 184 is screwed into threaded bores of the swingable member 169. A locking element 173 screwed on the threaded shaft of the adjusting screw 171 may be used to hold same in a predetermined adjusted position. A latch 174 swingably mounted at 175 on a plate 176 secured to the track 165 is arranged for cooperation with the edge 177 of the swingable member 169. A spring 178 arranged between a flange 179 of the plate 176 and the latch 174 tends to urge normally the latch against a stop 180, so that the latch is in engagement with the swingable member 169 and holds the effective edge 172 of the adjusting screw 171 in the path of the abutting member 184. Each latch-mechanism L₁, L₂, is provided with an electromagnet 181 arranged opposite the latch 174. Each electromagnet 181 may be individually energized for lifting the latch 174 into the position 174' shown in dash and dot lines in Fig. 8. The carriage 163 is under the action of a load 182 connected with the carriage by a cord 183 laid around a roller 185 as shown in Fig. 7. Said load 182 urges the abutting member 184 of the carriage 163 against the effective edge 172 of one of the stopping means 168 normally held in the path of the abutting member by the spring loaded latch 174.

When an apparatus equipped with the mechanism shown in Figs. 7 and 8 is used, at first the movable half-tone screen is brought into the position shown in Fig. 7, wherein the abutting member 184 abuts against the effective edge of the stopping means 168 of the first latch mechanism L₁, so that the half-tone screen 130 is at a standstill in front of the first portion of the negative. Thereupon, the first exposure is made. After said first exposure, the electromagnet 181 of the first latch-mechanism is energized, whereby the latch 174 thereof is lifted into the position 174' shown in dash and dot lines in Fig. 8, so that the abutting member 184 being under the action of the load 182 may swing the stopping means 168 about the pivot 179 out of its path into the position 168' shown in dash and dot lines in Fig. 8, whereby the half-tone screen 130 is automatically displaced one step through a distance *f* equal to its width *d*, until the abutting member 184 hits against the effective edge of the next stopping means 168 held in its path by the spring loaded latch of the next latch mechanism L₂. After the passing of the abutting member 184 under the stopping means 168 of the first latch mechanism L₁, the stopping means of the latter returns by its own weight into its normal position shown in full lines in Fig. 8, whereupon the electromagnet 75

181 of the first latch-mechanism may be de-energized for causing a locking of the stopping means by the spring loaded latch 174. Now, when the half-tone screen is held by the stopping means 168 of the latch mechanism L₂ at a standstill in front of a second portion of the negative being consecutive to the first portion of the negative, a second exposure may be made. After said second exposure, the electromagnet 181 of the second latch-mechanism is energized, whereby a further step-movement of the half-tone screen is obtained in the same manner as described above. The step by step movements of the half-tone screen and the exposures between the steps when the half-tone screen is held in its position by a stopping means of a latch-mechanism may be repeated as often as necessary in dependence on the number of latch-mechanisms arranged in the apparatus.

According to Fig. 7, the various latch mechanisms L₁, L₂, the number of which corresponds to the number of step-displacements to be carried out by the half-tone screen, are arranged only on the upper track 165. If desired, however, an equal number of latch mechanisms may also be arranged on the lower track 166 for cooperation with a second abutting member secured to the carriage 163 holding the half-tone screen 130.

For the sake of simplifying the explanation of the apparatus with a controlled step-by-step movement of the half-tone screen, the assumption has been made above, that the distance *e* between the indicating marks M₁, M₂, M₃ or the distance *f* between the effective edges 172 of the various stopping means 168 of the various latch-mechanisms L₁, L₂ is equal to the width *d* of the half-tone screen appearing in the window 154 of the mask 140. This assumption is correct, if the half-tone screen is in contact with the surface of the negative. In practice, however, there may be a slight space 199 (see Fig. 6) of a thickness of a few millimeters between the half-tone screen 130 and the negative 128. If this is the case, the distance between adjacent indicating marks or the distance between the effective edges of adjacent stopping means should be slightly larger (about $\frac{1}{2}$ to 2 millimeters) than the width *d* of the half-tone screen. The exact length of the distance may be readily found by calculations or a few experiments. The adjustable screws 171 of the embodiment shown in Figs. 7 and 8 permit an easy adjustment of the exact distance between the effective edges 172 of adjacent stopping means 168.

During above described methods for the reproduction of dot composed negatives the half-tone screen is moved step by step. However, the method for the reproduction of dot composed negatives with the positive and negative held in a fixed position relative to each other and to the optical axis of the objective may also be carried out with a continuous movement of the half-tone screen.

Fig. 9 illustrates diagrammatically the mechanism for a continuous drive of the half-tone screen and for making automatically exposures in timed relationship to the movement of the half-tone screen. It is understood, that the tracks 265, 266, the slidable carriage 263 holding the screen 230, and the flexible mask 249 laid around the rollers 242 take the place of the corresponding elements of the apparatus shown in Figs. 4 and 5, when an apparatus according to the invention is designed for a continuous movement of the half-tone screen. According to Fig.

9 a threaded spindle 286 is rotatably but axially immovably arranged in brackets 287 mounted on the stationary track 266. An element 288 attached to the carriage 263 has a threaded bore in engagement with the threaded portion of the spindle 286. A sprocket wheel 289 is keyed to one end of said spindle 286.

Another sprocket wheel 290 of exactly the same size and shape as the sprocket wheel 289 is keyed to a shaft 291 journalled in suitable bearings (not shown) of the apparatus. Furthermore, a disk-like shutter 260 is keyed to said shaft 291, so that said shutter 260 may be rotated by a rotation of the sprocket wheel 290. The shutter 260 arranged in front of the objective 223 has a series of equally spaced openings 292 each having a width g being a predetermined fraction of the distance h between adjacent openings.

A further sprocket wheel 293 is keyed to the driving shaft 294 of an electromotor 295. Furthermore, an idling wheel 296 is loosely but axially immovably arranged on said shaft 294. A chain 297 is trained around the sprocket wheels 289, 290, 293 and the idling wheel 296. As will be readily understood, a rotation of the driving shaft 294 of the electromotor 295 causes a rotation of the threaded spindle 286 and the disk-like shutter 260 at the same speed, as the sprocket wheels 289 and 290 are of the same size. Furthermore, as the half-tone screen 239 is moved along the negative 128 carried by the holder 132 by a rotation of the threaded spindle 286 and as a light flash is produced every time an opening 292 of the rotatable shutter 260 passes the objective 223, light flashes will be produced in a predetermined relationship to the movement of the half-tone screen 230.

As an example for the various relationships between the mechanisms of the apparatus for the production of a continuously coherent dot-composed reproduction of a positive on a negative the following dates may be given:

Assume that the negative 128 has a length i of 1 meter (see Fig. 3) and that 4000 dots 298 are to be produced at extremely small equal distances in a row on said negative 128 during a continuous movement of the half-tone screen 230 at a constant speed in the direction of the arrow B from the starting position shown in full lines into the end position 230' shown in dash and dot lines. Furthermore, suppose, the half-tone screen 230 has a width d of $1/10$ meter. Under these circumstances the half-tone screen 230 is to be moved into the position 230' through a distance $i+d=1^{1/10}$ meters, and 4400 instantaneous exposures are to be made at regular intervals. As mentioned above, 4000 dots are to be reproduced on the length $i=1$ meter of the negative 128; consequently, each dot has a width of $1/4000$ meter or $1/4$ millimeter, and likewise, the width j (Fig. 2) of a transparent dot of the half-tone screen 230= $1/4$ millimeter.

Furthermore, assume that the spindle 286 (Fig. 9) has 10 threads per centimeter; that the shutter 260 has four openings each having a width $g=1/10$ of the distance h between adjacent openings, and that the shutter 260 makes 1 revolution per second. Then the half-tone screen 230 will move 1 millimeter during 1 second or $1/4$ millimeter during $1/4$ of a second; furthermore, a light flash of $1/40$ of a second will pass through the half-tone screen every $1/4$ of a second.

As mentioned above, each transparent dot of the half-tone screen has a width j of $1/4$ of a millimeter and the half-tone screen is moved $1/4$ of a millimeter during $1/4$ of a second.

of a millimeter during $1/4$ of a second. Therefore, the transparent dots of the half-tone screen are moved through a distance equal to their width during $1/4$ of a second. Moreover, as mentioned above, a light flash of $1/40$ of a second passes through the half-tone screen every $1/4$ of a second. In other words, the time of the instantaneous exposure is $1/10$ of $1/4$ second, the time required for relative movement between the negative 128 and half-tone screen 230 for a distance of $1/4$ millimeter equal to the width of $1/4$ millimeter of a transparent dot of the half-tone screen.

The data given above are to be taken only as an example. Satisfactory results are obtained if the instantaneous exposures made automatically by the shutter at moments, when the half-tone screen is moved into a position wherein its transparent dots pass over the loci of the prospective dots on the negative, take about $1/10$ to $1/20$ of the time required for a movement of the half-tone screen through a distance equal to the width of a transparent dot of its pattern of dots. Furthermore, of course, a different type of a controlling mechanism could be used to obtain said features.

We have described preferred embodiments of our invention, but it is clear that numerous changes and omissions may be made without departing from the spirit of our invention.

What we claim is:

- 30 1. In a photographic apparatus for the production of dot-composed negatives from a positive, a stationary holder for a negative in said apparatus, a negative disposed in said holder, a mask adjacent said negative and having a window, and a dot-composed half-tone screen mounted in said window and adjacent said negative and being smaller than said negative and including a pattern of alternating transparent and opaque dots, each two adjoining like dots being spaced from each other for a certain distance in a predetermined direction, said screen being movable, with said mask, along said negative in a direction at a fixed angle to said predetermined direction, in combination with, means for moving said screen from one position to another along said negative comprising guiding means and a series of registry means intermediate said movable screen and said stationary holder, said registry means arranged to be spaced from each other for a distance constituting a multiple of said certain distance for preserving substantially exact dot-pattern continuity on said negative throughout the screen reproductions, and comprising a latch secured with relation to said screen and movable therewith, and a series of abutment means spaced from each other for said last named distance and associated with relation to said stationary holder and operable to be moved into the path of said latch engaging the same and to be moved out of said path for disengagement from said latch and for subsequent movement of said screen, and electrically controlled means for impelling said abutment means at least during one of said movements.
- 35 2. In a photographic apparatus for the production of dot-composed negatives from a positive, a stationary holder for a negative in said apparatus, a mask adjacent said negative and being movable along the same and having an opening, and a dot-composed half-tone screen mounted to said mask at said opening and movable therewith and disposed adjacent said negative and being smaller than said negative and including a pattern of alternating transparent and opaque dots, each two adjoining like dots being spaced from

- 50
- 55
- 60
- 65
- 70
- 75

each other for a certain distance in a predetermined direction, in combination with, means for moving said screen and mask, and registry means for holding said screen in selected positions opposite said negative and comprising, a latch carried at least with relation by said screen and movable therewith, a series of spaced abutment means movable in and out of the path of said latch and having a surface for engagement with said latch and disengagement therefrom to stop said screen at selected positions in its move under the impulse of said driving means and to release it for subsequent resumed move, respectively, each said surface spaced from an adjoining surface for a distance, adjusting means associated with each abutment surface for varying said distance to a predetermined multiple of said first named certain distance for preserving substantially exact dot-pattern continuity on said negative, and electrically controlled means operable to move said abutment means out of said path for latch release.

3. In a photographic apparatus of the class described, in combination, a dot-composed screen movable in front of a stationary negative, said screen arranged to produce a dot-continuous image in step-by-step repeated exposures when moved for at least a single accurately predetermined distance, and means for moving said screen along said negative for a multiple of said distance comprising driving means for movement of said screen in one direction, registry means for said negative and screen including a latch associated with said screen, a series of latch engaging members spaced substantially for said last named distance and independently of the movement of said screen movable in and out of the path of said latch, and adjusting means for each of said engaging members to vary the posi-

tion of effective engagement between said latch and a member said adjusting means including a screw and a threaded holder surrounding said screw and said screw being rotatable for axial movement within said holder.

4. In a photographic apparatus of the class described, in combination, a dot-composed screen including adjoining light and opaque spots and movable in front of a stationary negative, said screen arranged to produce a dot-continuous image in step-by-step repeated exposures when moved for at least a single accurately predetermined distance, and means for moving said screen along said negative for a multiple of the combined width of a light and opaque spot comprising driving means for movement of said screen in one direction, registry means for said negative and screen including a latch associated with said screen, a series of latch engaging members spaced substantially for said last named distance and independently of the movement of said screen movable in and out of the path of said latch, adjusting means for each of said engaging members to vary the position of effective engagement between said latch and a member, and a solenoid interconnected to an electric circuit and operable to effectuate at least one of the movements of each of said members.
